BREAK DOWN LOADING MECHANISM

Emil Keller, Detroit, Mich., assignor to Michigan Steel Corporation, a corporation of Michigan

Application April 1, 1931, Serial No. 526,977

12 Claims. (Cl. 214—7)

This invention relates to loading mechanism and particularly to an improved sheet-loading mechanism which transfers sheets from the rolls of a rolling mill and stacks them in vertical piles upon a platform, cradle or similar device which is readily movable from the vicinity of the mill.

In the co-pending application of J. H. Steele, Serial No. 485,019, filed December 29, 1930, and assigned to the assignee of the present invention, a sheet loading mechanism was disclosed wherein the sheets were moved along a conveyor to a table on which a frame was tiltable to cause the sheets to slide therefrom onto a cradle where they were retained in vertical position. The cradle was carried by a truck which was automatically movable laterally from the conveyor and table, a predetermined amount each time a motor was actuated, to regulate the number of sheets which were disposed in each stack. The platform or cradle was removed from the truck, after a predetermined number of stacks of sheets had been disposed thereon, by a crane or other suitable lifting device and a second platform was placed upon the truck to be filled with a plurality of stacks of sheets in the above mentioned manner.

My present invention provides improved means for handling and stacking the sheets which may be accomplished automatically by a motor or similar actuating device and which may be adjusted to handle sheets of various sizes.

Accordingly, one object of my invention is to provide a conveyor for transferring and stacking a plurality of sheets of metal as they are delivered from the rolls of a mill, which is an improvement over similar types of structure heretofore employed.

Another object of my invention is to provide a tiltable frame for a conveyor of the above mentioned type, which shall cause the sheets to slide therefrom into angular position on a platform, after which a continued movement in rotation of the frame causes the end thereof to move the sheets into vertical position.

A further object of my invention is to provide an actuating mechanism for the frame of the conveyor which moves it into tiltable and beyond a vertical position for effecting the stacking of the plates.

A still further object of my invention is to provide a carriage for supporting a platform upon which the sheets are stacked, which is movable laterally from the conveyor and which supports a mast whereon retaining means are provided for supporting the sheets in stacked vertical position.

A further object of my invention is to provide means for regulating the height of the engaging and supporting means for the sheets and for permitting its rotation about the mast to enable a crane or similar carrying mechanism to engage and remove the platforms from the truck.

Numerous other objects and features of novelty of my invention will be either specifically pointed out or will become apparent when referring, for a better understanding of my invention, to the following description in conjunction with the accompanying drawings, wherein—

Figure 1 is a broken view, in side elevation, of a conveyor and stacking mechanism which embodies features of my invention.

Fig. 2 is a plan view of the structure shown in Fig. 1.

Fig. 3 is an end view, partly in section and partly in elevation, of the structure shown in Figs. 1 and 2.

Fig. 4 is an enlarged sectional view of the structure shown in Fig. 1, taken along the line 4—4 thereof.

Fig. 5 is an enlarged plan view, partly in section, of the mast of the structure shown in Fig. 2.

Fig. 6 is an enlarged broken sectional view of the structure shown in Fig. 1, taken along the line 6—6 thereof.

Fig. 7 is an enlarged broken view of a structure, similar to that shown in Fig. 3, illustrating a modified form which my invention may assume, and

Fig. 8 is a broken view of a structure, similar to that shown in Fig. 7, illustrating a further modified form of my invention.

My invention comprises in general a conveyor 10 which is mounted for pivotal movement on one end of a table 11 in prolongation thereof. Rollers 12 are disposed in angular relation on the conveyor 10, extending slightly above the supporting portion thereof, and a plurality of wheels 13 are disposed on the table, the top surface thereof extending above the top members of the table. The conveyor 10 is provided with an arcuate end 14 which is disposed adjacent to a "billy" roll 15 supported on the delivery side of a rolling mill 16 as shown in Fig. 2.

A pair of wheels 17 support the outer end of the conveyor 10 for angular movement about a pivot 18 which connects one side of the conveyor with the table. In this arrangement, the end 14 of the conveyor 10 may be rolled laterally to any point relative to the "billy" roll 15 for receiving a sheet 19 as it is delivered from the mill 16, as shown in Fig. 2.

The angularly disposed rollers 12 shift the sheet laterally across the conveyor 10, as it is drawn therealong toward the table 11, to have the plate centered on the table as it is drawn across the wheels 13 thereof.

As pointed out in the above-mentioned co-pending application, after a plurality of passes are made across a sheet of steel to reduce its thickness, it becomes cooled to such an extent that it must be reheated before the final thickness or gauge of sheet is obtained. The metal is rolled to less than twice the desired sheet thickness during the first series of passes through the mill and the sheets thus effected are then delivered to my conveyor and table from which they are stacked for the purpose of being conveyed to a pickling bath.

The sheets at this point of the rolling operation are known as "break-downs" which require the pickling operation in order to have the scale and dirt removed therefrom before they are again heated and passed through the mill. My conveyor eliminates the necessity of employing two or more men for handling the sheets and stacking them in the proper manner for pickling. By having the stacking mechanism counterbalanced and operated through levers, motors or gears, the effort, heretofore required to operate similar stacking devices, is considerably reduced.

A pair of laterally extending arms 21, project from the side of the table 11, for supporting a bar 22 upon which a frame 23 is pivoted. The frame is provided with a plurality of wheels 24 and a roller 25 which are disposed at right angles to the wheels 13 supported on the table. The frame is rotatable about the bar 22 and is provided with a counterweight 26 for balancing the weight of the frame about the bar.

The frame 23 is tiltable through an angle greater than 90 degrees by an arm 27 and a link 28, the former of which is rigidly attached to a rotatable bar 29, the latter of which is pivoted to the arm and the frame. A handle 31 is attached to the end of the bar 29 as a means for actuating the arm 27 and the link 28, for rotating the frame about the supporting bar 22. During this movement, the break-down is lifted from the wheels 13 of the table 11 by the wheels 24 of the frame, across which it rolls as the frame is tilted, for a purpose which will be described more fully hereinafter.

A pair of rails 32 are disposed below, and in longitudinal relation with, the frame 23 upon which a truck 33 is supported for movement away from and toward the frame. A drum 34 is mounted on the side of the table 11, opposite to that on which the frame 23 is pivoted, and is operated by means of a hand wheel 35 and a ratchet wheel 36, to wind a cable 37 thereon, in either direction of movement of the hand wheel. The cable 37 extends downwardly from the drum 34 under a pair of pulleys 38, one end 39 thereof being connected directly to the axle of the truck, the other end 40 thereof extending about a pulley 42, disposed at the opposite end of the rail 32 from that at which the pulleys 38 are mounted and is attached to the truck adjacent to the point at which the end 39 of the cable is attached.

With this construction, the truck 33 may be moved laterally of the frame 23 by the clockwise movement of the hand wheel 35, after the ratchet wheel 36 has been disengaged by a finger 43 to permit the rotation of the hand wheel. The ratchet wheel and finger when engaged, prevent

the movement of the truck away from the frame 23 by a force other than that applied through the wheel after the finger has been released from the ratchet.

A hollow mast 44 is supported on the rear end 80 of the truck 33, upon the upper end of which a closure member 45 is retained by a screw 46. A hollow bolt 47 supports a bracket member 48 in pivotal relation to the top of the closure member 45 in which a ball race 49 is provided. A ball race 51 is provided in the undersurface of the bracket member 48 in registry with the ball race 49, the race 51 being closed at each of its ends for the purpose of retaining balls 52 therein. A pulley wheel 53 is mounted in the bracket 54 of the member 48, by a pin 55. A cable 56 is supported by the pulley in such manner as to extend through the hollow bolt 47 to within the mast 44.

The outer end of the cable 56 is connected to a bracket 57, disposed on the side of a collar 58, 95 which is in slidable relation to the mast 44, as shown more clearly in Fig. 6. A counterbalancing weight 59 is disposed within the mast and supported on the opposite end of the cable 56 for the purpose of counter-balancing the weight of 100 the collar 58 and an arm 61 mounted thereon. The arm 61 is pivoted on trunnions 62, which are supported on the side of the collar 58, and is retained in substantially horizontal position through the engagement of the underside of the 105 arm with the bracket 57. A plurality of pivotal fingers 63 are mounted in predetermined position along the arm 61 for a purpose which will be explained hereinafter.

To retain the sleeve 58 in adjusted position relative to the mast 44, an inwardly biased pin 64 is mounted on one side of the sleeve, opposite to that to which the arm 61 extends, that engages any one of a plurality of holes 65 which are disposed in longitudinal vertical relation along the rear 115 side of the mast 44. A fulcrum 66 extends rearwardly from the sleeve 58 above the pin 64, on the end of which an actuating member 67 is pivoted by a pin 68. The actuating member engages the inner surface of the head 69 of the pin 64, for 120 the purpose of effecting its outward movement against the bias of the spring 71, which retains the pin 64 in engagement with the hole 65. By means of a member 67 the pin is withdrawn from the hole and the sleeve may be adjusted in height 125 by having the collar 58 moved longitudinally along the mast until the pin 64 engages another hole 65 for retaining the sleeve and therefore the arm 61 at a predetermined height above the frame 23.

When the pin 64 is moved from the hole 65 the 130 sleeve 58, and therefore the arm 61, may be revolved about the mast, out of a position over the truck 32. The counterbalancing of the sleeve by the weight 59 and the ball bearing supported bracket member, permits an easy adjustment of 135 the sleeve and arm 21 to any desirable position relative to the mast.

A pair of I-beams 72 are mounted laterally across the surface of the truck 33, in spaced relation as shown in Fig. 3, for the purpose of supporting a platform 73, shown in dot and dash line, for receiving the sheets as they are tilted by the frame 23. The platform 73 is thereby spaced from the top surface of the truck 33, to permit a platform of a lifting truck, or the chains of a 140 crane, to pass thereunder for the purpose of raising the platform from the beams 72 and for transporting the platform along with the sheets stacked thereon, away from the mill. The platform 73 is provided with a plurality of holes (not 145 150

shown) in which rods 74, shown in Fig. 3 in dot and dash lines, are insertable for retaining a predetermined number of break-downs in vertical stacks, which are spaced from each other by the 5 bars.

The operation of my conveying and stacking device will now be described. As a sheet 19 passes from the mill 16 over the "billy" roll 15, it engages the rollers 12 of the conveyor 10 and is drawn up 10 the conveyor by a workman. During its upward movement, it is adjusted laterally, because of the inclination of the rollers 12, to be disposed centrally of the table 11. The operator rolls the sheet 19 across the wheels 13 until it is entirely 15 on the table, when the same or a second operator, moves the handle 31 to cause the arm 27 to rotate in a clockwise direction to apply a force to the link 28, to tilt the frame 23.

The wheels 24 of the frame, lift the sheet out of 20 engagement with the wheels 13 of the table and permit the plate to roll across the surface of the frame 23 laterally of the table until the end thereof engages the bar 74. The end of the sheet slides down the bar, as the table 23 is continued to be 25 rotated, until it rests upon the platform 73 adjacent to the lower end of the bar 74. Further movement of the frame 23 causes the upper end thereof to rotate the sheet or "break-down" about its lower end until it is in parallel relation to the 30 bar 74.

The sleeve 55 is adjusted to permit the sheet to pass under the arm 61 and to just clear the undersurface of the arm in order that the sheet 35 engages a finger 63 as it is tilted against the bar 74. The finger returns to its original position in the plane of movement of the sheet to prevent the sheet from falling backwardly against the frame when the frame is returned to its original position in engagement with the table 11. The fingers 40 63 are so positioned on the arm 61 that only a plurality of the sheets are retainable by each finger and an indication is made to the operator that the sheets in one stack have reached a predetermined number and that another set of bars 45 74 are to be placed across the front surface of the stack in order to space the predetermined number of sheets from the next succeeding group.

As each succeeding row of bars is mounted in the platform 73 the hand wheel 35 is actuated in 50 a clockwise direction to move the truck 33, and therefore the platform 73, away from the table to permit another group of plates to be stacked thereon. In this manner the platform is entirely 55 covered with a predetermined number of spaced, stacked group of plates which are then ready to be moved from the truck.

If a crane is employed for engaging and transporting the platform 73, the member 67 is moved outwardly away from the mast, to draw the pin 64 from engagement with the hole 65, to permit the sleeve 55 to be revolved about the mast which carries the arm 61 out of a position over the platform. The supporting member for the crane may then be attached to the platform and the 65 platform raised and moved away from the beams 72. The sleeve is then revolved to its original position and the pin 64 is biased by the spring 71 into the hole 65 of the mast.

If a truck, having a raisable platform, is employed for moving the platform 73 and the stacks of sheets, the raisable platform is run under the platform 73 which is raised from the beams 72 and moved along with the truck laterally of the truck 33. In case the arm 61 should interfere 75 with this movement, it may be tilted about the

trunnions 62 of the sleeve to permit the arm 61 to clear the bars 74 or the top ends of the sheets. After the platform 73 and the sheets are moved from the beams, a second platform 73 is placed thereon and the hand wheel 35 is then operated 80 in a counter-clockwise direction to move the truck 33 frontwardly into its original position, which is that shown in Fig. 3.

Referring to Figs. 7 and 8, I have illustrated modified forms of my invention, which include 85 automatic actuating means for rotating the frame 23 toward and away from the table 11. In Fig. 7, I have shown a segment 75 of a gear which has been attached to the bar 29, in place of the handle 31 heretofore referred to, and have provided a rack 76 which is slidable along a surface 77, in mesh with the teeth of the gear segment 75 to cause the segment and the bar 29 to be rotated. A cylinder 78 has a piston 79 mounted therein, from which a rod 81 projects through the front 90 end of the cylinder in engagement with the end of the rack 76 for effecting its reciprocation.

A suitable fluid, such as air, oil, steam or the like, is conducted through pipes 82 and 83 to each 100 end of the cylinder, the supply of fluid through either of which is controlled by a valve 84. When the valve is turned, to effect a flow of fluid through the pipe 82, the piston and therefore the rack is moved toward the left, which movement causes the arm 27 to be rotated in a clockwise direction 105 and the frame 23 to be rotated away from the table 11. When the valve is reversed, to have the fluid flow through the pipe 83, the piston and the rack is reciprocated to the right causing the arm 110 to be rotated in a counter-clockwise direction to return the frame 23 to horizontal position on the table 11.

In Fig. 8, I have shown a motor 85 provided with a gear 86 in mesh with the gear segment 75. The gear 86 is actuated by the motor 85 through 115 a suitable train of gears 87 having an idling gear which is insertable in the gear train for the purpose of reversing the direction of rotation of the gear 86. A suitable magnet is employed for inserting the reversing gear in mesh with the gear 120 train for operating the gear 86 in a reverse direction. It is to be understood that the gear train need not be provided with an idling gear when the motor itself is reversed by changing the direction of flow of current therethrough, which 125 may be effected through a double-throw switch in a well known manner. In either arrangement the reversing of the rotation of the arm 27, for causing the frame 23 to be tilted against the top surface of the table, will be effected.

A circuit to a switch 92 is connected either directly to the motor for reversing its rotation or to a magnet (not shown) which inserts the idling gear in the gear train, for effecting a reversal of rotation to the gear 86. To have the reversing 135 operation occur automatically, after the table 23 has reached a predetermined angle, I have provided a suitable switch actuating mechanism which will now be described.

A rod 88 is supported on the table for sliding 140 movement in bearings 89 and has, on its outermost end an element 91 mounted in the path of movement of the arm 27 which effects the movement of the rod to the right, as the frame 23 reaches the end of its clockwise rotative movement. This movement of the rod actuates the switch 92 to either reverse the direction of flow of current to the motor or to actuate the magnet, for the purpose of inserting the idling gear in mesh with the gear train, either of which actua- 145 150

tions effects the reverse rotation of the gear 86 which returns the arm 27 and therefore the frame 23 to a horizontal position.

A bell crank 93 has one arm mounted in the path of movement of the frame 23, while the other arm engages a collar 94 mounted in fixed relation to the rod 88. The engagement between the arm of the bell crank and the collar causes the rod 88 to be moved to the left when the opposite arm of the bell crank is engaged by the frame 23 as it returns to horizontal relation with the table 11. The switch 92 is actuated by the rod, as it moves to the left, to open the circuit to the motor or to the reversing magnet and when another break-down has been moved upon the table 11, the starting button of the switch 92 is actuated to complete the circuit to the motor, which caused its actuation through the above described cycle for effecting the stacking of the break-downs.

It will thus be seen that I have provided an improved stacking device, for sheets of metal in the nature of break-downs, which is automatic in operation and which eliminates the manual effort heretofore required for placing the plates in stacks. A counter-balancing means is employed on the stacking frame and also on the support for the retaining bar which is adjustable, and which may be moved vertically on a mast or revolved thereabout with very little effort. A hand wheel is provided for moving the platform and the truck laterally of the table as the breakdowns are stacked thereon and controlling means is provided adjacent to the hand wheel for operating the actuating means for the stacking frame, the tilting of which may be accomplished automatically.

While I have described and illustrated several embodiments of my invention, it will be apparent to those skilled in the art that various changes, omissions, additions and substitutions may be made therein without departing from the spirit and scope of my invention, as set forth in the accompanying claims.

I claim as my invention:

45 1. In a sheet handling device which includes in combination, a substantially horizontal table for receiving said sheet, a frame mounted in pivotal relation thereto for removing the sheets from the table, rollers on said frame over which the sheet

50 is advanced when the frame is initially tilted, and means for tilting said frame through an angle greater than ninety degrees relative to said table for causing the sheets to slide therefrom and for moving the sheets to a vertical position thereafter.

55 2. In a sheet handling device including, in combination, a substantially horizontal table for receiving said sheets, a frame pivotally mounted on said table for removing the sheets therefrom, rollers on said frame over which the sheet is advanced when the frame is initially tilted, and motor means for tilting said frame to and from said table through an angle greater than ninety degrees.

60 3. A sheet handling device which includes, in combination, a substantially horizontal table for receiving said sheets, a frame pivotally mounted on said table for angular movement laterally thereof, rollers on said frame over which the sheet is advanced when the frame is initially tilted, a fluid actuating device for tilting said frame through an angle greater than ninety degrees, to and from said table for removing the sheets therefrom, and means for controlling the actuation of said device.

65 4. In a sheet handling device which includes, in

combination, a substantially horizontal table for receiving said sheets, a frame mounted in pivotal relation thereto, rollers on said frame over which the sheet is advanced when the frame is initially tilted, means for tilting said frame through an angle greater than ninety degrees relative to said table, the first portion of the movement causing the sheet to be slid into angular position while the last portion of the movement causes the unpivoted end of the frame to engage the sheet and raise it to vertical position.

80 5. In a device for stacking sheets as they are delivered from a mill which includes, in combination, a conveyor upon which the sheets are moved, a movable element for receiving said sheets, a tiltable frame for transferring the sheets from said conveyor to said element, a mast on said element, a sleeve slideable on said mast and an arm extending from said sleeve for engaging and retaining the end of said sheets.

90 6. In a device for stacking sheets on a member including, in combination, a conveyor upon which the sheets are moved, a table associated with said conveyor, means on said table for rotating the sheets through an angle of substantially ninety degrees, a movable element for receiving said sheets, a mast on said element, a sleeve slideable on said mast, an arm supported on said sleeve and means for positioning said sleeve on said 100 mast.

105 7. In a device for stacking sheets on a member including, in combination, a conveyor upon which the sheets are moved, a table associated with said conveyor, means on said table for rotating the sheets through an angle of substantially ninety degrees, a movable element for receiving said sheets, a mast on said element, a sleeve slideable on said mast, an arm supported on said sleeve, means for positioning said sleeve on said mast and means for counter-balancing the weight of 110 said sleeve and arm.

115 8. A movable element for receiving the sheets from a stacking machine which includes, in combination, means for moving said element, a mast 120 mounted on said element, a sleeve on said mast, a plate enclosing the top of said mast and provided with a raceway, a pulley bracket mounted for angular movement on said plate having a cooperating raceway, ball bearings in said raceway, a cable 125 extending over said pulley engaging said sleeve and a member engaging the other end of said cable for counterbalancing the weight of said sleeve.

130 9. In a device for stacking sheets, a hollow mast for supporting a sheet retaining element for longitudinal and rotatable movement thereon, a plate provided on the top of said mast having a raceway, a pulley bracket pivoted on said plate and provided with a cooperating raceway, ball 135 bearings in said raceway, a cable extending over said pulley and through said pivot within said mast having one end connected to said sleeve and a weight within said mast attached to the other end of said cable.

140 10. A hollow mast supported on a movable element for positioning a plurality of sheets thereon, a sleeve longitudinally and rotatably movable upon said mast for supporting said arm, a plate on the top of said mast provided with a raceway, a pulley bracket pivoted on said plate and provided with a cooperating raceway, ball bearings in said raceways, a cable extending over said pulley, one end of which is attached to said sleeve, the other end of which extends within the mast 145 150

and a weight within said mast supported on the end of the cable extending therewithin.

and a weight on the other end of said cable for counterbalancing the weight of said sleeve and arm.

11. A hollow mast supported on a movable element for positioning an engaging arm for a plurality of sheets which are stacked on said element, a sleeve longitudinally and rotatably movable on said mast for supporting said arm, a plate on the top of said mast provided with a raceway, a pulley bracket pivoted on said plate and provided with a segment of a raceway in cooperating relation with said raceway in the plate, ball bearings retained in the segment of the raceway and cooperating with the raceway in the plate, a cable extending over the pulley and engaging the sleeve,

12. In a device for stacking sheets, a hollow mast supported on a movable element for retaining a sheet engaging arm in predetermined extended relation thereto, a sleeve supporting said arm and engaging the mast in such manner as to be longitudinally and rotatably movable thereon, means for counterbalancing the sleeve and arm, means for permitting said counterbalancing means to rotate relative to said mast and means for positioning said sleeve on said mast.
